UNITED STATES PATENT OFFICE.

CALVIN K. SCHADE, OF CANTON, OHIO.

LANTERN.

No. 832,167.

Specification of Letters Patent.

Patented Oct. 2, 1906.

Application filed May 14, 1906. Serial No. 316,839.

To all whom it may concern:

Be it known that I, CALVIN K. SCHADE, a citizen of the United States, residing at Canton, in the county of Stark and State of Ohio, 5 have invented new and useful Improvements in Lanterns, of which the following is a specification.

This invention relates to improvements in lanterns.

10 The object of the invention is to provide an improved means for raising and lowering the globe-holding frame and globe and for locking the same in either of said positions.

15 A further object is to provide an attachment of this character which will be simple, strong, durable, and inexpensive in construction, efficient in operation, and well adapted to the purpose for which it is designed.

20 With the above and other objects in view the invention consists of certain novel features of construction, combination, and arrangement of parts, as will be hereinafter described and claimed.

25 In the accompanying drawings, Figure 1 is a side view of a lantern, showing the arrangement of the attachment when the globe is down or in closed position. Fig. 2 is a similar view showing the position of the attachment when the globe is raised or in an open 30 position. Fig. 3 is a side view, partly in section, taken at right angles to Figs. 1 and 2, with the parts in the position as shown in Fig. 1; and Fig. 4 is a similar view with the parts in the position as shown in Fig. 2.

35 Referring more particularly to the drawings, 1 denotes the lantern, which may be of any style or make and which is here shown as a tubular lantern comprising a base portion 2, in which is arranged an oil receptacle or 40 font. On the base is arranged a burner-supporting mechanism 3, and to said burner-supporting mechanism and the base 2 are connected upwardly-projecting draft-tubes 4, which support the cap or top portion of the 45 lantern and through which the under draft of air is supplied to the burner.

Arranged on the burner is a globe-supporting plate 5, which may be of the usual or any suitable construction and is here shown as 50 having arranged thereon an annular upwardly-projecting flange 6, in which is secured the globe-protecting frame 7, which is here shown and is preferably constructed of wire bent to form outwardly-disposed upwardly-projecting protecting-bars 8. These bars 8 are brought together and connected by

a suitable fastening-clip 9, from which the wire rods are bent to form upwardly-projecting inclined loops 10, which encircle the globe, as shown. In the upper portion of the loops 60 10 are formed short loops or bends 12, with which are adapted to be engaged hooks 13, formed on the lower ends of a globe-holding rod or bar 14, which is arranged in a globe-holding sleeve 15, slidably mounted in the 65 top piece of the lantern-frame. Said sleeve 15 is provided on its upper end with a cap 16, which is spaced therefrom and supported above the same by means of lugs 17, as shown.

Arranged below the globe-supporting plate 70 5 is a globe-raising shaft 18, said shaft being provided on its opposite ends with upwardly and outwardly bent cranks 19, which are journaled in bearings 20, formed in the inner sides of the tubes 4. The shaft 18 is also provided with a centrally-disposed rearwardly-projecting crank 21, pivotally connected to the under side of the globe-plate 5 by means of a clip 22 or other suitable connection.

Pivotedly mounted upon the shaft 18 adjacent to one side of the plate 5 is a curved lifting-lever 23, said lever being preferably pivotally mounted on the shaft 18 by bending the end of the lever into a series of coils 24, which loosely engage the shaft to permit 85 the lever to swing freely thereon. The lever 23 is adapted to work through and engage an eye 25, formed on the right-angularly-bent end of one of the guard-frame wires 8, whereby when said lever is raised or swung up- 90

wardly on the shaft 18 the curved portion of the same will bear against said eye, which will rock the shaft 18 rearwardly in its bearings in the tube 4, thereby turning the centrally-disposed crank portion thereof up- 95 wardly, which will raise the globe-plate 5, together with the globe and protecting-frame, upwardly to the position shown in Figs. 2 and 4 of the drawings. The lever 23 is provided adjacent to its pivoted end with a 100 sharp bend which forms a locking-recess 26, in which the eye 25 will spring when the globe is in a lowered or closed position, thereby locking the lever down and holding said globe and frame in a closed position. 105 Adjacent to the outer end of the lever 23 the same is bent to form an offset or shoulder 27, over which the eye 25 is adapted to spring when the lever is up and the globe and frame in a raised or open position, thereby locking 110 said globe and frame up in a raised position. The outer end of the lever 23 is bent to form

an eye or loop-shaped handle or finger-piece 28, by means of which the same may be readily manipulated.

By means of an attachment such as herein 5 shown and described the globe and its supporting-frame may be quickly raised or lowered to an open or closed position and locked in such positions against casual or accidental movement.

10. From the foregoing description, taken in connection with the accompanying drawings, the construction and operation of the invention will be readily understood without requiring a more extended explanation.

15. Various changes in the form, proportion, and the minor details of construction may be resorted to without departing from the principle or sacrificing any of the advantages of this invention as defined by the appended 20 claims.

Having thus described my invention, what I claim as new, and desire to secure by Letters Patent, is—

25. 1. A globe raising and lowering attachment for lanterns, comprising a lifting-shaft, a lever pivotally mounted on said shaft, and an eye on the guard-frame of said globe to engage the lever pivotally mounted on said shaft, substantially as described.

30. 2. A globe raising and lowering attachment for lanterns comprising a cranked raising-shaft, an eye arranged on the guard-frame of the globe, a curved lifting-lever pivotally mounted on said shaft to engage said 35 eye, and means formed on said lever to lock

the globe-supporting frame in a closed or open position, substantially as described.

3. A globe-lifting attachment for lanterns comprising a shaft having on its ends cranks, said cranks being journaled in bearings in the 40 lantern-frame, a centrally-disposed crank formed in said shaft and pivotally connected to the globe-supporting plate, an eye formed on the globe-guard frame, a curved lifting-lever pivotally mounted on said crank-shaft 45 to engage said eye, and means formed on said lever to hold said lantern-globe in a raised or lowered position, substantially as described.

4. A globe-lifting attachment for lanterns 50 comprising a crank-raising shaft journaled in the frame of the lantern, an eye formed on the globe-guard frame, a lifting-lever pivotally mounted on said shaft to work through said eye, a locking-recess formed in said lever 55 near its pivotal connection to engage said eye when the globe-frame is down thereby locking the same in a closed position, a locking-shoulder or offset formed near the outer end of said lever to engage said eye when the 60 globe-frame is raised, thereby locking the same up, and a handle formed on the outer end of said lever, substantially as described.

In testimony whereof I have hereunto set my hand in the presence of two subscribing 65 witnesses.

CALVIN K. SCHADE. [L. S.]
